UNITED STATES PATENT OFFICE

2,577,672

MAKE-UP GALLEY

Frank Bernik, Mount Vernon, Wash.

Application March 1, 1948, Serial No. 12,319

19 Claims. (Cl. 276—43)

1

This invention relates to new and useful improvements in make-up galleys for use in offset or job work in printing and newspaper plants and has for its primary object to lock the type within the galley at the exact and correct measurement required.

Another object of this invention is to enable a printer, setting the type in the galley, to make use of the point system and to obtain a correct measurement of the type and to hold the said type in place at the correct measurement.

Another object of this invention is to provide a printer's galley, with a movable squaring member or gage arm, which is longitudinally moved on the galley in conformity with the point system or pica graduations subscribed on the side of the galley, so that the squaring arm is uniformly regulated and controlled and the correct measurement required is obtained.

Another important object in association with the exact and correct measure being imparted to the squaring arm is the provision of a locking device adapted to lock the squaring arm in the correct and exact measured position.

Another important object of this invention is to provide means whereby the squaring arm may be completely detached or removed from the galley.

These and ancillary objects are attained by this invention, a preferred embodiment of which is set forth in the following description and illustrated in the accompanying drawings, wherein:

Figure 1 is a plan view of a galley, illustrating the improved squaring arm and the actuating means therefor;

Figure 2 is an enlarged fragmentary perspective view of one end of the galley, shown generally in Figure 1;

Figure 3 is a sectional view taken substantially on the line 3—3 of Figure 1;

Figure 4 is a transverse sectional view taken substantially on the plane of line 4—4, illustrating the means provided for guiding the squaring arm and for locking the arm in desired placement;

Figure 5 is a cross sectional view taken substantially on the plane of line 5—5 of Figure 1;

Figure 6 is a vertical longitudinal sectional view taken substantially on the line 6—6 of Figure 1;

Figure 7 is a fragmentary sectional view taken substantially on the line 7—7 of Figure 1 and;

Figure 8 is a view in perspective of the structure employed to effect the guide and locking arrangement of the squaring arm.

2

Referring now more particularly to the drawings, wherein similar characters of reference designate corresponding parts throughout, the numeral 10 designates a conventional printer's galley, having a customary upraised side wall 12 and a similar end wall 14, within which type is hand set or grouped in the usual method.

Suitably secured to the opposite side from the upraised side wall 12 of the oblong galley and 10 adapted to serve as an opposed side wall in co-operating relationship with the wall 12 is a longitudinally extending block 16. The block 16 is suitably secured by customary attaching means to the end wall 14 and by means of screw 20 to the galley. Suitably journalled at one end within the channel formed in the block 16 is an elongated actuating rod 22, being suitably threaded. The extending terminus of the actuating rod 22 is suitably journalled at one end 15 of the block with the opposite extremity thereof suitably reduced and extending through the end of the block, with a knob 24 secured on the projecting terminal thereof by a set screw 26. Suitably fashioned longitudinally in the inner 20 side wall of the block 16 is a T-shaped track or 25 guide-way 30, for a purpose to be later described.

A conventional squaring arm 32 is adapted to be longitudinally movable on the galley 10 by rotation of the finger piece 24, which imparts 30 rotation to the actuating rod 22. Integrally extending from the triangular T-shaped squaring arm 32 is a carrier block 34, which is angularly formed and is adapted to overlie the longitudinal block 16. Suitably secured to the under 35 surface of the carrier 34 is an arcuate guide 36, which is suitably riveted or otherwise secured as at 38 to the under surface of the carrier block and is suitably exteriorly threaded to engage the threaded shank of the actuating rod 22, where- 40 by rotation of the shank 22 coincidentally and correspondingly moves the squaring arm 32.

Suitably scribed on the block 16 on either side of the actuating rod 22 journalled longitudinally in the channel formed in the block are pica 45 graduations, corresponding to the conventional point system, utilized in type setting, which is marked as to six and twelve points and as to the inch scale. The actuating rod 22 has suitably secured on the extending portion thereof be- 50 tween the finger knob 24 and the extremity of the block 16 a similarly subscribed or marked collar 42. Thus, it can be seen that through manual rotation of the finger knob 24, rotation is imparted to the actuating rod 22, which 55 through the medium of the threaded guide block 36 moves the squaring arm or gage 32 on the

galley to position the type thereon. In rotating the finger piece 24, exact control can be had of the amount of revolution needed being imparted to the elongated screw or actuating rod 22, through the medium of aligning the line gage set 40 on the block 16 with the pica graduations carried by the collar 42, so that various forms of type may be accommodated, such as the great primer, little pica, the interlinear or the like.

Suitable means are provided for locking the squaring arm 32 in predetermined and selected positions and for preventing vertical movement of the squaring arm relative to the galley. The means preferred comprises a pin 50, having an offset head 52, which is adapted to move in the head portion of the T-shaped slot or guideway 30 formed longitudinally in the side surface 28 of the block 16. The head portion 52 of the pin 50 is movable through an oblong slot 54 formed in the side of the squaring arm adjacent the carrier. The pin 50 has an extending exteriorly threaded terminus 56, upon which is suitably received an attaching cap 58. Interposed between the attaching cap 58, which is received on the extremity 56 of the pin 50 is an elongated support plate 62, having securing apertures 64 disposed therein, through which extend attaching screws 66, which secure the plate 62 to the outer surface of the side of the squaring arm 32, adjacent the carrier block. Integrally extending from the attaching plate 62 and suitably secured around aperture 68 formed therein is a series of cam shaped rings 70. Suitably received on the extending pin 50 is a cylindrical case or clutch collar 72 having a series of cam shaped semi rings 76 on the inner end thereof, which are complementary to the fixed cam series 70. An actuating or finger pin 74 radially extends from the collar 72 and serves to rotate the collar with a holding collar 76 extended into the outer end thereof. Interposed between the cap 58 and the collar 72 is a holding collar 76, having a slot 78 formed therein, to accommodate securely the protruding pin 80, disposed on the shank of the pin 50, with radially extending finger pins 82 formed on the collar. A coil spring 84 is received around the shank of the pin 50, between the plate 62 and the cap member 58 and serves to bias or urge the head portion 52 of the pin 50 outwardly.

Thus, with reference to Figure 8 of the drawings, it is to be noted that rotation of the collar 76 by the finger pin 82 correspondingly moves or rotates the pin 50 and the head 52. Thus, when the finger pins 82 are moved upwardly the head 52 is disposed in vertical placement and is secured within the head portion of the slot or guideway 30. In this position, movement of the collar 72 through the finger piece 74 causes the complementary series of work shaped rings 70 and 76 to be moved into an extended position, thereby forcing the head portion 52 securely against the block 16.

To remove the squaring arm 32 from the galley 10, half rotation of the collar 76, moves the head portion 52 out of engagement with the slot 30, the pin 50 being urged forward by the spring 84.

Thus, it can be seen that there is provided a galley, whereby correct measurement of the type may be obtained and also, the type may be locked, by means of the locking arrangement of the squaring arm in selected positions on the galley. Also, to effect a repair on the actuating rod or to replace the squaring arm with a larger

or smaller arm or gage, the arm or gage is detachable from the galley. However, since many other objects and purposes of this invention will become apparent to those skilled in the art, upon a perusal of the foregoing description, in view of the accompanying drawings, it is to be understood that certain changes may be effected thereon, within the spirit of the invention and within the scope of the appended claims.

10 Having described the invention, what is claimed as new is:

1. A galley comprising a type receiving plate having an elongated block on one of the side edges thereof, a type positioning and locking arm slidably carried by said block and disposed transversely on the plate, actuating means disposed in said block for moving said arm longitudinally on the plate, a guideway formed on the inner surface of the block, a guide and locking assembly carried by said arm and including a pin having a head portion slidably and rotatably disposed in the groove, means for selectively rotating and axially reciprocating said head portion in the groove to disengage said head from said groove, and means for locking said head portion in the groove whereby the arm is locked against longitudinal movement on the plate.

2. A galley comprising a type receiving plate having an elongated block on one of the side edges thereof, said block being formed with an elongated channel on the upper surface thereof, a type positioning and locking arm slidably carried by said block and disposed transversely on the plate, a U-shaped carrier for said arm slidably mounted on said block, an exteriorly threaded saddle plate carried by the undersurface of the bight of the carrier, an exteriorly threaded actuating rod journaled in said channel and engageable with said saddle plate for moving said arm longitudinally on the plate, a guideway formed in the inner side of the block, a guide member carried by said arm and slidably and rotatably disposed in said guideway, means for selectively rotating and axially reciprocating said member in the guideway to disengage said member from said guideway and means for locking said member in the guideway whereby the arm is locked against longitudinal movement on the plate.

3. A galley comprising a type receiving plate having an elongated block on one of the side edges thereof, said block being formed with an elongated channel on the upper surface thereof, a type positioning and locking arm slidably carried by said block and disposed transversely on the plate, a U-shaped carrier for said arm slidably mounted on said block, an exteriorly threaded saddle plate carried by the undersurface of the bight of the carrier, an exteriorly threaded actuating rod journaled in said channel and engageable with said saddle plate for moving said arm longitudinally on the plate, a guideway formed in the inner side of the block, a pin carried by said arm, an enlarged head on said pin, means for rotating said pin for positioning said head in the guideway, cam means for moving said head into frictional locking engagement of the guideway and means for releasing said head from the guideway.

4. A galley comprising a type receiving plate, an elongated block mounted on one of the side edges of the plate, a type positioning and locking arm slidably associated with the block and transversely superimposed on said plate, actuating means in said block for moving said arm

longitudinally on the plate, a guideway formed on the inner side of the block; a guide member carried by said arm and slidably disposed in said guideway, a fixed plate secured on said arm, said member being slidably and rotatably disposed through said plate, a movable member associated with said guide member, complementary means on said movable member and fixed plate for locking said guide member against longitudinal movement in the guideway, and means for selectively rotating and axially reciprocating said guide member to disengage said guide member from said guideway.

5. A galley comprising a type receiving plate having raised side and end walls, an elongated block mounted on the side edge of the plate opposite the side wall, a type positioning and locking arm slidably mounted at one end on said block and disposed transversely on the plate, a guideway formed on the inner side of the block, a plate fixed on said arm and disposed parallel with said guideway, a guide pin disposed through said plate and slidably and rotatably positioned in said guideway, a first rotatable sleeve concentrically disposed on said pin, complementary means formed on said fixed plate and sleeve for frictionally locking said pin in the guideway, a second sleeve slidably and non-rotatably attached to said guide pin for selectively rotating said guide pin, and means operatively connected to said pin for reciprocating the same out of said guideway when said pin is rotated into a predetermined angular position.

6. In a type setting device the combination of a type receiving plate having a flat working surface and an upstanding flange formed at its front and one longitudinal edge, of a block mounted on the opposing longitudinal edge, a type positioning and locking arm slidably disposed transversely on the working surface of the plate, one end of said arm being slidably and detachably mounted on the block, said block having a guideway therein, said guideway including first and second relatively perpendicular portions, said first portion opening on the inner side of said block, actuating means disposed longitudinally in the block and engageable with said end of the arm for moving the arm longitudinally on the plate, an apertured plate fixed on said end of the arm and disposed parallel with the guideway, a guide pin disposed through said plate, an enlarged head on said pin slidably and rotatably disposed in said second portion of said guideway, means for selectively rotating and axially reciprocating said head in the guideway to disengage said head from said guideway, a rotatable sleeve concentrically disposed on said pin, complementary means on said sleeve and fixed plate for frictionally locking said head in the guideway.

7. In a type setting device the combination of a type receiving plate having a flat working surface and an upstanding flange formed at its front and one longitudinal edge, of a block mounted on the opposing longitudinal edge having a guideway opening on the inner side thereof, a type positioning and locking arm slidably disposed transversely on the working surface of the plate, one end of said arm being slidably and detachably mounted on the block, actuating means disposed longitudinally in the block and engageable with said end of the arm for moving the arm longitudinally on the plate, and apertured plate fixed on said end of the arm and disposed parallel with the guideway, a guide member disposed through said plate and having an enlarged portion on one

end slidably and rotatably received in the guideway, means disposed on and associated with said member for selectively rotating and axially reciprocating said enlarged end in the guideway to disengage said enlarged portion from said guideway, a rotatable sleeve concentrically disposed on said pin, complementary means on said sleeve and fixed plate for frictionally locking said head in the guideway.

10. 8. The combination of claim 7, wherein said locking means includes cam means.

9. In a type setting device, the combination of a type receiving plate having a flat working surface and an upstanding flange formed at its front and one longitudinal edge, of a block mounted on the opposing longitudinal edge, a type positioning and locking arm slidably disposed transversely on the working surface of the plate, one end of said arm being slidably and detachably mounted on the block, actuating means disposed longitudinally in the block and engageable with said end of the arm for moving the arm longitudinally on the plate, an apertured plate fixed on said end of the arm and disposed parallel with the guideway, a guide member disposed through said plate and having one end slidably received in the guideway, means disposed on and associated with said member for positioning said end in the guideway, a rotatable sleeve concentrically disposed on said pin, complementary means on said sleeve and fixed plate for frictionally locking said head in the guideway, and means for releasing said end from the guideway said positioning means including a finger radially formed on

35 the opposing end of the member, a sleeve concentrically positioned on said member and having means formed on the inner surface for receiving said finger, means formed on and extending from said sleeve for rotating the same.

40. 10. The combination of claim 9, wherein a cap is secured on the opposing end of the member for retaining said sleeves in position on the member and resilient means is disposed about the member and engaged against the finger for moving the inserted end of the member outwardly from the guideway.

11. In a galley including a flat rectangular working surface formed with an upstanding flange at its front and one longitudinal edge and 50 a block mounted on the opposing longitudinal edge, and a type positioning arm slidably mounted at one end on the block and disposed transversely on the working surface of the galley; the improvement which comprises means for guiding and locking said arm on the block, said block being formed with a guideway on the inner side thereof, said means including a guide pin disposed through said mounted end of the arm and having one end slidably received in the guideway, a cap member secured on the opposing end of the pin, a sleeve concentrically disposed on the pin between the cap member and the mounted end of the arm, cam means operated by said sleeve for moving said inserted end of the pin into frictional locking engagement of the guideway whereby said arm is locked against longitudinal movement.

12. In a galley including a flat rectangular working surface formed with an upstanding flange at its front and one longitudinal edge and 70 a block mounted on the opposing longitudinal edge, and a type positioning arm slidably mounted at one end on the block and disposed transversely on the working surface of the galley; the improvement which comprises means for guid-

75

ing and locking said arm on the block, said block being formed with a guideway on the inner side thereof, said means including a guide pin disposed through said mounted end of the arm, an enlarged end on said pin slidably received in said guideway, a cap member on the opposing end of the pin, a sleeve concentrically disposed on said pin between the mounted end of the arm and the cap member, means associated with said sleeve for rotating said pin to move said enlarged end into sliding relation with the guideway, cam means for moving said enlarged end of the pin into frictional locking engagement with the guideway and means for urging said enlarged end from the guideway responsive to said pin rotating means.

13. The combination of claim 12, wherein said pin rotating means includes a lateral finger on the shank of said pin, a guide slot for said finger formed on the inner wall of the sleeve and an operating member extending from the outer wall of said sleeve.

14. The combination of claim 12, wherein said cam means includes a fixed cam series formed on the mounted end of the arm, a cylindrical member concentrically and rotatably disposed on the sleeve and having a cam series formed on one end thereof, and complementary to said fixed cam series.

15. The combination of claim 12, wherein said last means includes a spring disposed about the shank of the pin.

16. A type positioning device for use with a galley comprising an elongated block adapted to be secured to a galley, said block having a guideway therein, a type positioning arm slidably mounted on said block, said guideway including a first and a second mutually perpendicular portion, said first portion opening on one side of said block, a guide pin carried by said arm slidably and rotatably received in said first portion of said guideway, a transverse head on the end of said pin slidably and rotatably received in said second portion of said guideway, a first manually operable means carried by said pin for selectively rotating and axially reciprocating said pin to engage and disengage said head from said guideway, and a second manually operable means carried by said pin for selectively locking said arm against sliding movement.

17. A type positioning device for use with a galley comprising an elongated block adapted to be secured to a galley, said block having a guideway therein, a type positioning arm slidably mounted on said block, said guideway including a first and a second mutually perpendicular portion

8
tion, said first portion opening on one side of said block, a guide pin carried by said arm slidably and rotatably received in said first portion of said guideway, a transverse head on the end of said pin slidably and rotatably received in said second portion of said guideway, a first manually operable means carried by said pin for selectively rotating and axially reciprocating said pin to engage and disengage said head from said guideway, and longitudinally expansible means interposed between said first manually operable means and the side of said block for selectively locking said arm against sliding movement.

18. A galley gauge comprising an elongated block having a guideway formed therein, said guideway including first and second relatively perpendicular portions, said first portion opening into a first side of said block, an arm having a portion thereof slidably abutting said first side of said block, said portion of said arm having an aperture therein, a guide pin extending through said aperture, a transverse head on the end of said pin slidably and rotatably disposed in said second portion of said guideway, a first sleeve slidably and non-rotatably disposed on said pin, a cap on the other end of said pin, a second sleeve rotatably mounted on said pin, a first cam means carried by said portion of said arm which abuts said first side of said block, a second cam means carried by the end of said second sleeve which registers with said first cam means, said second sleeve being rotatable relative to said first cam means to positively urge said pin outwardly of said guideway and thereby lock said arm against sliding movement.

19. The combination of claim 18 including a spring disposed about said pin and terminally engaging said first and second sleeves.
